ATTORNEY

UNITED STATES PATENT OFFICE.

FREDERICK W. GORDON, OF PITTSBURG, PENNSYLVANIA.

GAS-BURNER FOR FURNACES.

SPECIFICATION forming part of Letters Patent No. 244,746, dated July 26, 1881.

Application filed March 18, 1881. (No model.)

To all whom it may concern:

Be it known that I, FREDERICK W. GORDON, of Pittsburg, Allegheny county, Pennsylvania, have invented certain new and useful Improvements in Gas-Burners for Furnaces, of which the following is a specification.

This invention relates to gas-burners applicable to the furnaces of steam-boilers, &c. The object is to secure a more economical consumption of the gas, and to produce a burner of simple and economical construction, which will be convenient for erection, cleaning, &c.

The invention has reference to improvements in means, and does not involve any principles of combustion not at present well known to the arts.

In the accompanying drawings, Figure 1 is a front elevation, part section, of a boiler-furnace fitted with two of the improved gas-burners; Fig. 2, a vertical longitudinal section of the same through a gas-chamber, and Fig. 3 a perspective view of the burner proper.

In Figs. 1 and 2 is shown a battery of two boilers with furnace suited for solid fuel and gas. C is the firing-door; D, ash-door; E, grate; T, side wall of furnace; L, bridge-wall; K, partition-walls between main furnace and gas-chambers P; J, the gas-burners, one on each side of main furnace, and issuing into the gas-chambers; G, the burner-pipe leading to gas-main, and I the air-inlets to the burners. The burners J inject mingled air into the gas-chambers, where it ignites and moves upward, inward, and rearward. When solid fuel is used on the grate the gases all mix and move together. The burner J is a box having an inlet, G, from the gas-main, and having its furnace side open and issuing into the gas-chambers. The burner will be understood by an inspection of Fig. 3. Air-inlets I in the sides of the burner are continued so as to present sheet issues at the open end of the burner. The air-conduits are seen to be of flattened section at the issue, and to partially block up the gas-out-

let, which becomes divided itself into several flat conduits. The gas is thus injected in sheets interposed with air. By this arrangement of issues the gas and air enter in interposed sheets, and the diffusion before ignition is about perfect. The gas deposits matter on surfaces with which it comes into contact, and the air-conduits in the burner, by the arrangement shown, furnish horizontal surfaces for this deposit. A door, N, at the face of the burner allows these simple surfaces to be readily and perfectly cleaned by passing cleaning devices into the gas-conduits between the air-conduits.

The position of the burners in front of the furnace enhances the accessibility of the affair; but the same burner would work well if placed in the usual position above the grate.

Valves for the control of the gas should be fixed at proper points in the gas-inlet.

I claim as my invention—
1. In a gas-burner for furnaces, the combination and arrangement of a series of alternate interposed gas and air issue orifices of flattened section, located one above another, substantially as and for the purpose set forth.

2. In a gas-burner for furnaces, the combination, with a burner-body having a gas-inlet, a cleaning-door, and an open issue side, of air-conduits arranged in the burner-body, as set forth, having side admissions, and having flattened outlets arranged in and dividing the gas-outlet, substantially as set forth.

3. The combination, in a boiler-furnace, with the gas-burners J, boilers A, grate E, and ash-chamber F, of the gas-chambers P, located between the side walls of the furnace and the low side walls of the ash-chamber and grate-furnace, substantially as set forth.

FRED. W. GORDON.
